UNITED STATES PATENT OFFICE

114,677

DESIGN FOR A BOTTLE OR SIMILAR CONTAINER

Walter M. Jakway, Hollywood, Calif.

Application January 18, 1939, Serial No. 82,402

Term of patent 7 years

To all whom it may concern:

Be it known that I, Walter M. Jakway, a citizen of the United States, residing at Hollywood, in the county of Los Angeles and State of California, have invented a new, original, and ornamental Design for a Bottle or Similar Container, of which the following is a specification, reference being had to the accompanying drawing, forming part thereof.

In the drawing, Fig. 1 is an elevational view, and Fig. 2 is a plan view, of a bottle or similar container showing my new design.

I claim:

The ornamental design for a bottle or similar container, as shown.

WALTER M. JAKWAY.
